UNITED STATES PATENT OFFICE

DAVID A. CHRISTIANSON, OF ATLANTA, GEORGIA, ASSIGNOR, BY MESNE ASSIGNMENTS, TO THE AD-BAG SALES CORPORATION, A CORPORATION OF DELAWARE

DESIGN FOR A BAG

Application filed September 8, 1932. Serial No. 44,774. Term of patent 3½ years.

To all whom it may concern:

Be it known that I, DAVID A. CHRISTIANSON, a citizen of the United States, residing at Atlanta, in the county of Fulton and State of Georgia, have invented a new, original, and ornamental Design for Bags, of which the following is a specification, reference being had to the accompanying drawing, forming part thereof.

The figure is a perspective view of a bag, showing my new design.

I claim:

The ornamental design for a bag, as shown.
D. A. CHRISTIANSON.
